UNITED STATES PATENT OFFICE.

CHARLES A. A. RAND, OF CHICAGO, ILLINOIS.

PLATFORM-FOLDING DEVICE FOR REAPERS.

No. 856,986.

Specification of Letters Patent.

Patented June 11, 1907.

Application filed March 29, 1907. Serial No. 365,232.

To all whom it may concern:

Be it known that I, CHARLES A. A. RAND, a citizen of the United States, residing at Chicago, in the county of Cook and State of Illinois, have invented a new and useful Improvement in Platform-Folding Devices for Reapers, of which the following is a complete specification.

This invention relates to reapers provided with folding platforms, and more particularly to the members employed in securing the platform in its elevated position and in its normal working position, the object being to provide simple and effective means for accomplishing such results, and means in which the platform brace is employed to support the platform in both its up and down positions.

A further object in view is to provide a pendent strut for supporting the grain side of the reaper when raising the said platform.

Other improvements in the details of construction will appear in the following description and in the accompanying drawings, in which—

Figure 1 represents a rear elevation, partly in section, of the main portion of a reaping machine. Fig. 2 is a plan of the platform support and parts associated therewith. Fig. 3 is a central longitudinal section taken through the parts shown in Fig. 2. Fig. 4 shows a transverse section through the platform support, taken on the line 4—4 of Fig. 2. Fig. 5 represents a view of the under side of the outer end of the platform support, taken as indicated by the line 5—5 in Fig. 3. Fig. 6 shows a fragmentary rear elevation of the upper or pivotal end of the pendent strut on the platform support. Fig. 7 represents a plan view of the reel arm support with the roller of the reel arm resting thereon; and Fig. 8 is an elevation of the parts shown in the preceding figure, taken as indicated by the line 8—8 in Fig. 1.

In the drawings the main frame is designated by the numeral 1, the main supporting wheel by 2, and the grain wheel by 3. On the main frame 1 is mounted the reaper head 4, provided with the usual reel or rake arms 5, and to the member 1¹ of the main frame is hinge-connected the folding platform frame 6, the pivotal axis being formed by the pin 6¹.

The parts of the reaper thus far mentioned are common to all such machines, and no claim to novelty is made thereto. The new

features reside in the platform support and elements connected therewith, which will now be described.

To the underside of the main frame 1 are secured the two angle bars 7, the upper members, or legs, of said bars being arranged horizontally to oppose each other and are placed a slight distance apart in order to leave a slot 8, in which slides the platform brace 9. 65 These angle bars extend outwardly beneath the grain platform 6 and have rigidly secured to their outer ends the wheel and brace casting 10, which has formed thereon the bracket 10¹ adapted to receive the grain wheel rack 70 3¹. This casting 10 is provided with an aperture 10², as shown, in which slides the brace 9. On the rear side of the casting 10 is pivotally mounted the spring-held pawl, or latch, 11, which engages the teeth 3² on the wheel 75 rack 3¹, thereby enabling the grain wheel 3 to be readily attached or detached from the casting 10. The outer end of the brace 9 is pivotally mounted in the bracket 12, which is fixed on the underside of the platform, the 80 pivotal bearing being formed by means of the pin 13. Surrounding the projecting end of this pin 13, and reacting between the platform and brace 9, is the coil spring 14 (see Fig. 5), which tends to press the free end of 85 said brace downwardly. The free end of the brace 9 terminates in the laterally bent end 9¹, which slides beneath and is held from upward movement by the rear angle bar 7. As the platform 6 is raised from its normal to 90 elevated position, the bent end 9¹ slides under the angle bar from its inner to its outer position, or from the full line position of Fig. 2 to the dotted line position of Fig. 3, in which latter position the laterally bent end 95 9¹ rests upon the ledge 10³ of the casting 10.

The brace 9 is locked in its horizontal position, or in the position in which it securely holds the platform in normal working position, by means of the transversely movable 100 lever 15, which engages the underside of the end of said brace 9.

Pivoted to the angle bars 7, at a point substantially coincident with the pivotal axis 6¹ of the platform 6, is the pendent 105 strut 16, with its pivotal axis at 16¹. This strut 16 is preferably U-shaped, with the legs extending upwardly and pivoting to the outer side of the angle bars 7. The rear leg of the strut 16 is bent in such a manner that 110 when folded up it will lie parallel to its supporting angle bar, and secured to said leg, in

the rear of the pivotal axis 15¹ of the lever 15, is a shoulder 17^a, which, with the bend in said leg, operates to hold the lever 15 in position beneath the end of the brace 9 and lock 5 same in its horizontal position. To lock the strut 16 in either its folded or its vertical position, the following described means are employed: A sector strap 18 is secured to the inner side of the rear angle bar 7 by means of 10 the rivets 18¹, and in the arcuate portion of this strap are formed the apertures 18^a and 18^b, adapted to be engaged by the spring-held latch pin 19. This latch pin 19 is carried by the strut 16 and engages an aperture 15 therein, the same bracket 17 in which said latch pin is mounted also having formed thereon the shoulder 17^a. When the end of the latch pin 19 is made to engage the aperture 18^a in the sector 18 the strut will be 20 locked in its vertical position or in a position to support the grain side of the reaper; but when the end of said latch is made to engage the aperture 18^b, the strut will be locked in its folded position. If at the same time that 25 the strut 16 is folded the lever 15 be brought back behind the shoulder 17^a, this lever will simultaneously be locked, which will also lock the brace 9 in its horizontal position. To prevent the strut 16 being pressed into 30 the soil a foot 16^a of considerable breadth is secured to the lower transverse member thereof.

Before folding the platform 6 it is necessary to raise the reel or rake arm overlying 35 same to a non-interfering position and sustain it there. This is done by providing a spring-locked swing arm 20 mounted on the reaper frame, or more properly on the frame of the reaper head. The boss 20^a, in which 40 the swing arm is mounted, is provided with the notch 20¹, the axis of said arm projecting through the boss and taking the coil spring 20². By pulling the arm outwardly a slight distance and compressing the spring 20², the 45 arm can be swung to either its upper or its lower position. When in its upper position the arm 20³ thereof will engage the roller 5¹ of the reel arms 5, as shown in Fig. 8 and in dotted lines in Fig. 1.

50 To fold the platform for transportation the latch pin 19 is withdrawn and the strut 16 dropped to a vertical position and there locked by permitting the latch pin to engage the aperture 18^a in the sector 18. The lever 55 15 is then moved to the left, or from the full to the dotted line position of Fig. 2, thereby releasing the brace 9. The grain wheel 3 is then detached from the outside of the platform and the overlying rake arm 5 lifted up 60 and its roller 5¹ allowed to rest upon the top of the swing arm 20, which has been turned to its upper position. The platform is now raised, the platform brace moving from the full to the dotted line position shown in Fig. 65 3, as before explained, and the coil spring 14

pressing the brace against the ledge 10³ of the casting 10 to prevent any binding action of these parts in such movement. When the platform has been raised to its elevated position, the spring 14 will press the bent end 9¹ 70 to a position on top of the ledge 10³, where it will rest until the platform is again lowered. The grain wheel 3 is now attached to the casting 10, as before explained, after which the strut 16 is folded up and the machine is 75 ready for transportation.

What I claim as my invention, and desire to secure by Letters Patent, is:

1. In a platform folding device for reapers, in combination, a reaper frame, a platform frame hinge-connected thereto, a platform support fixed rigidly to the reaper frame and made to extend outwardly beneath said platform, a grain wheel adapted to be attached either to the outer end of the platform or to 80 the outer end of the platform support, and a brace having at one end a pivotal connection with the platform and adapted to rigidly secure the same in either its folded position or in its normal working position. 90

2. In a platform folding device for reapers, in combination, a reaper frame, a platform frame hinge-connected thereto, a platform support fixed rigidly to the reaper frame and made to extend outwardly beneath said platform, a grain wheel adapted to be attached either to the outer end of the platform or to the outer end of the platform support, and a brace having at one end a pivotal connection with the platform and at the 100 other end an interlocking connection with the inner end of the platform support for rigidly sustaining the said platform in its working position, and also an interlocking connection with the outer end of said support for 105 rigidly sustaining the platform in its elevated position, substantially as and for the purpose specified. 110

3. In a platform folding device for reapers, in combination, a reaper frame, a platform frame hinge-connected thereto, a platform support fixed rigidly to the reaper frame and made to extend outwardly beneath said platform, a grain wheel adapted to be attached either to the outer end of the platform or to the outer end of the platform support, a brace having a pivotal connection at its outer end with the platform and interlocking connections at its inner end with the platform support whereby said brace is adapted to 120 hold the platform either in normal working position or in a folded position, and a spring operating to swing said brace away from the platform. 115

4. In a platform folding device for reapers, in combination, a reaper frame, a platform frame hinge-connected thereto, a platform support fixed rigidly to the reaper frame and made to extend outwardly beneath said platform, a grain wheel adapted to be at- 125 130

tached either to the outer end of the platform or to the outer end of the platform support, a brace having at its outer end a pivotal connection with the platform and adapted to rigidly secure the same in either its folded position or in its normal working position, and a pendent strut pivotally secured to the platform support for sustaining the grain side of the reaper while changing the grain wheel from the platform to the platform support.

5. In a platform folding device for reapers, in combination, a reaper frame, a platform frame hinge-connected thereto, a platform support fixed rigidly to the reaper frame and made to extend outwardly beneath said platform, a grain wheel adapted to be attached either to the outer end of the platform or to the outer end of the platform support, a brace having at one end a pivotal connection with the platform and adapted to rigidly secure the same in either its folded position or in its normal working position, a lever for locking said brace to secure the platform in its normal working position, and a pendent strut arranged to lock said lever in its brace-locking position and to also sustain the grain side of the reaper while changing the grain wheel from the platform to the platform support.

6. In a platform folding device for reapers, in combination, a reaper frame, a platform frame hinge-connected thereto, a platform support fixed rigidly to the reaper frame and made to extend outwardly beneath said platform, said support comprising two angle bars arranged a slight distance apart to form a slot between their opposing edges, and a

wheel and brace casting binding together the outer ends of said angle bars, a grain wheel 40 adapted to be attached either to the outer end of the platform or to said wheel and brace casting, a brace having a sliding connection with said casting and a pivotal connection at one end with said platform and 45 adapted to rigidly secure the same in either its folded position or in its normal working position, a lever for locking said brace to secure the platform in its normal working position, and a pendent strut arranged to lock 50 said lever in its brace-locking position and to also sustain the grain side of the reaper while changing the grain wheel from the platform to the wheel and brace casting.

7. In a platform folding device for reapers, in combination, a reaper frame, revolving reel arms mounted thereon, a platform frame hinge-connected to said reaper frame, a platform support fixed rigidly to the reaper frame and extending outwardly beneath said 60 platform, a grain wheel adapted to be attached either to the outer end of the platform or the platform support, a brace having at one end a pivotal connection with the platform and adapted to rigidly secure the same in 65 either its folded position or in its normal working position, and a spring-locked swing arm mounted on the reaper frame and arranged to engage and support one of the reel arms when the platform frame is in its elevated position.
